UNITED STATES PATENT OFFICE.

CHARLES A. BULL, OF ALBION, NEBRASKA.

AUTOMOBILE-LOCK.

1,233,973.

Specification of Letters Patent. Patented July 17, 1917.

Application filed April 26, 1917. Serial No. 164,796.

To all whom it may concern:

Be it known that I, CHARLES A. BULL, a citizen of the United States, residing at Albion, in the county of Boone and State of Nebraska, have invented certain new and useful Improvements in Automobile-Locks; and I do declare the following to be a full, clear, and exact description of the invention, such as will enable others skilled in the art to 10 which it appertains to make and use the same.

This invention relates to improvements in safety devices and particularly to an improved lock for gasolene engines used on automobiles and various other places where the engine and associated parts are adapted to move from place to place.

The primary object of this invention is to provide a locking valve for internal combustion engines, the same being extremely simple in construction, thereby decreasing to a minimum the cost of manufacture.

Another object of the invention is to provide a locking valve which will prevent the 25 operation of the engine when the valve is in locked position, the location thereof being such that the removal or tampering of the valve cannot be done with the hope of starting the engine.

30 A still further object in view is to provide a locking valve which may be locked independently of the ordinary butterfly valve located in the intake manifold.

With these and numerous other objects in view, my invention resides in the novel features of construction and the combination and arrangement of the several parts as will be hereinafter more fully described and pointed out in the specification and claims.

40 In the accompanying drawings:

Figure 1 is a fragmental sectional view of an intake manifold and carbureter with my locking valve applied;

Fig. 2 is a horizontal section on the plane 45 of line 2-2 of Fig. 1;

Fig. 3 is a vertical section on the plane of line 3-3 of Fig. 2;

Fig. 4 is a horizontal section on the plane 50 of line 4-4 of Fig. 3;

Fig. 5 is a sectional view on the plane of line 5-5 of Fig. 3;

Fig. 6 is a top plan view of the casing which carries the locking valve;

Fig. 7 is a detail perspective view of the lock and disk supporting shaft; and, 55

Fig. 8 is a top plan view of the lock.

Similar numerals of reference are used to indicate corresponding parts in the several views.

Reference is now had to the drawings in 60 which the usual manifold 1 is shown provided with the short connecting pipe 2 and the carbureter 3 having the ordinary gas control butterfly valve 4 which is operated by a rod connected to the arm 5 on the upper end of the shaft on which the valve is mounted.

The carbureter 3 is supplied with gasolene through the pipe 6 and after the gasolene has been carbureted, it passes through the 70 passageway in the casing or union 8, through short pipe 2 to the manifold from which it passes into the cylinders.

The casing or union 8 as shown in the drawings has laterally extending attaching 75 plates or flanges 9 which have threaded apertures therein adapted to be aligned with apertures in contacting flanges 10 on each end of said union and to receive threaded bolts 11 therethrough to secure said union 80 in proper position and suitable gaskets clamped between said flanges to form a gas tight joint.

A butterfly valve 12 is rigidly secured to a shaft 13 which is rotatably mounted in 85 what will be termed upper and lower bearings in the casing or union 8, the aperture forming the upper bearing opening into a large circular recess 14 whose wall is offset at 15, as shown in Figs. 3, 5 and 6, substantially one-quarter of its circumference to form stops 16 and 17 whose purpose will be hereinafter described.

The lock 18 may be of any desired type and its casing may be formed integral with 95 the union 8 or may be separate therefrom and be provided with a longitudinally extending lug or pin 19 secured to its inner end and projecting into a socket 19' formed in the outer flat face 7' of a laterally extending enlarged portion 7 of the union, for 100 the purpose of preventing rotation of the

casing in relation to the union and then having the abutting edges of the lock casing 18 and the union 8 brazed or otherwise secured together.

5. Extending longitudinally from the inner end of the rotary cylinder 20 of the lock is a flat lug 20' adapted to be received between the pair of longitudinally extending ears 21 on the upper end of the shaft 13, said ears and lug having alined apertures therein to receive a connecting pin 22, one end 22' extending into the offset portion 15 of the recess 14 in the union and the other end extending to a point adjacent the wall of the

15. It will be readily seen that when the butterfly valve 12 is to be opened, the rotary cylinder 19 is given a one-quarter turn by the key 23 and further movement in this direction is prevented by the end 22' of the connecting pin abutting the stop 17 at one end of the offset portion of the circular recess 14 and when the valve is in closed position, the said end of the pin contacts with the 25 other stop 17 at the opposite end of the offset portion 15.

It is well known that unauthorized persons have often removed valves and locks arranged in the feed pipe and bridged the 30 broken part or valve by a flexible tube through which the gasoline readily flows. By positioning the locking valve between the manifold and carbureter, it is seen that removing or breaking said valve would render the engine useless, since the gasoline must necessarily pass through the carbureter before entering the manifold.

From the foregoing description of the construction of the operation of my improved automobile lock, the manner of applying the same to use and the operation thereof will be readily understood, and it will be seen that I have provided a simple and efficient device of this character for carrying out the objects of the invention, and in view of the simple construction, it is readily seen that the manufacturing cost is reduced to a minimum.

I claim:

50. 1. In a device of the class described, a casing having a passageway therethrough to aline with the passageway in the intake manifold of a gas engine, a laterally extending enlarged portion of said casing, said enlarged portion having a circular recess in its outer flat face, a shaft rotatably mounted in upper and lower bearings in the casing, said upper bearing opening through the bottom of the circular recess, the wall of said 55 recess being offset substantially one-quarter of its circumference to form stops, said shaft having a pair of parallel spaced ears extending longitudinally from the upper end thereof into the recess, said flat face having a 60 socket therein spaced to one side of the circu-

lar recess, a lock casing secured to the aforesaid casing and one end abutting the flat face of said enlarged portion, said lock casing having a longitudinally extending lug on its inner end projecting into said socket to prevent 70 rotation thereof, a rotary cylinder in said casing, said cylinder being longitudinally alined with the aforesaid shaft, and having a longitudinally extending lug received between the aforesaid pair of ears, said lug 75 and ears being apertured and receiving a pin therethrough, one end of said pin projecting into the offset portion to abut the aforesaid stops when the cylinder of the lock is given a one-quarter revolution in either direction, 80 and a disk in said casing secured to the shaft to close the passageway.

2. In a device of the class described, a casing having a passageway therethrough to aline with the passageway in the intake manifold of a gas engine, a laterally extending enlarged portion on said casing, a shaft 85 rotatably mounted in upper and lower bearings in said casing, a lock casing on said enlarged portion, a rotary cylinder in said lock casing, said enlarged portion having a circular recess therein adjacent the inner end of said cylinder, said cylinder having a longitudinally extending lug on its inner end projecting into the recess, the wall of said recess being offset substantially one-quarter of its circumference to form stops, said upper bearing opening into the recess, a pair of parallel spaced ears extending longitudinally from the upper end of said shaft and projecting into said recess, said ears receiving the aforesaid lug therebetween, said ears and lugs having apertures therein receiving a pin therethrough to connect the shaft and cylinder, one end of said pin projecting into the offset portion, whereby when the cylinder is given a one-quarter revolution in either direction the aforesaid one end of the pin will abut one of the stops to prevent further rotation, and a disk secured to said shaft and adapted to close the passageway.

3. In a device of the class described, a casing having a passageway therethrough to aline with the passageway in the intake manifold, a shaft rotatably mounted in bearings in the casing, a circular recess in the outer face of said casing, one bearing opening into said recess, the wall of said recess being offset substantially one-quarter of its circumference to provide stops at each end of said offset portion, a lock casing mounted on the aforesaid casing, a rotary cylinder in said lock casing and longitudinally alined with said shaft, said cylinder having a longitudinally extending lug on its inner end projecting into the recess, said shaft having longitudinally extending parallel spaced ears on its end projecting into the recess, said ears receiving said lug therebetween, said ears and lug being apertured and 130

receiving through the apertures a connecting pin, one end of said pin projecting into the offset portion, whereby upon a one-quarter revolution of the cylinder in either direction, said pin will strike one of the stops and prevent further rotation, and a disk secured to said shaft and adapted to close the passageway.

In testimony whereof I have hereunto set my hand in the presence of two subscribing ¹⁰ witnesses.
